A. L. SOWERBY,
FOUNTAIN PEN.
APPLICATION FILED JUNE 5, 1918.

1,306,394.

Patented June 10, 1919.

INVENTOR:
A. L. SOWERBY
BY: *Frank Oldham*
ATTORNEY

UNITED STATES PATENT OFFICE.

ARTHUR LICHFIELD SOWERBY, OF BACONSTHORPE, HOLT, ENGLAND.

FOUNTAIN-PEN.

1,306,394.

Specification of Letters Patent. Patented June 10, 1919.

Application filed June 5, 1918. Serial No. 238,368.

To all whom it may concern:

Be it known that I, ARTHUR LICHFIELD SOWERBY, a citizen of the United Kingdom of Great Britain and Ireland, and resident 5 of Baconsthorpe, Holt, in the county of Norfolk, England, have invented certain new and useful Improvements in and Relating to Fountain-Pens, of which the following is a specification, such as will enable 10 others skilled in the art to which it appertains to make and use the same.

This invention relates to improved means for filling fountain pens and refers to that type of pen in which a collapsible sac is provided and has arranged alongside it a plate 15 for the purpose of compressing the sac so that when the pen is dipped into a supply of ink and the pressure of the plate is removed, (by the rotating of a knob at the end 20 of the barrel,) the elasticity of the sac when regaining its normal, *i. e.*, expanded, shape will draw a supply of ink into the pen and thus fill it.

My invention consists of an improved 25 method of pressing the plate upon the sac and withdrawing it therefrom by which a satisfactory charge of ink is obtained. In addition to this the device I have constructed is easily manipulated, small and neat in appearance, and not likely to get out of order 30 and the construction is such that the operating mechanism is to all intents and purposes locked when not required.

My invention may be broadly described as 35 consisting in providing adjacent to the pressure plate a spring, say a leaf spring, one end of which is anchored toward the nib of the pen and the other is movable lengthwise in the barrel of the pen by a rotatable screw 40 device attached to the opposite end of the pen and so constructed and arranged that by a turning movement, in one direction, a nut which coöperates with the movable end of the spring is caused to travel a short distance down the inside of the barrel and thus bend or bow the spring causing it to push the plate upon the sac and deflate the latter, while the reverse rotation removes the spring or allows it to return to its normal 45 straight or flat position inside the pen, thus lifting the plate from the sac or allowing it to be pressed back by the sac when it expands.

The screwing device may be of any suitable kind but I preferably fit a screw plug

into the end of the pen and provide the plug with a screw carrying a non-rotatable nut said screw having an unthreaded extension which is passed through the plug and attached to a head outside same by which it 60 can be turned, the said screw having also an annular rib between the threaded portion and unthreaded part adapted to bear against the inside of the plug to prevent the screw being withdrawn therethrough. As the 65 screw is turned the nut moves a short distance along the inside of the pen in one direction of screw rotation with corresponding travel of the nut, the latter presses upon the end of the spring and bows it, while 70 turning the screw in the other direction reverses the travel of the nut and either draws back the spring or allows it to assume its normal straight position. The spring may be attached to the pressure plate by a lug 75 or clip stamped therefrom engaging one or two holes in the spring.

I will now describe my invention with reference to the accompanying drawings, in which, one method of carrying the invention 80 into effect is shown.

Figure 1 shows, largely in section, a fountain pen to which my invention is applied and in which the sac is in its expanded position.

Fig. 2 is a substantially like view of a pen with the sac compressed.

Fig. 3 shows details of the spring and compressing plate.

Fig. 4 is a section, at line 4—4 of Fig. 2. 90

In these drawings the barrel *a* contains sac *b* and pressure plate *c*. To the end of the barrel I have fitted a screw plug *d*, having centrally arranged in it a screw *e* carrying a nut or cross piece *f*, said screw 95 having an extension *g* attached to a finger-piece or knob *h* by which the screw can be turned from outside the pen. A shoulder or rib *i* is provided and fits within a recess in the plug *d* and prevents the removal of the screw *e* through the plug. In this example along the inside of the pen a leaf or like spring *j* is fitted and has one end anchored at *k* over a ring *k'* fitted in an annular groove in the pen. Toward its other 100 end the spring is supported by a like ring *l* and has its extremity positioned in a recess *m* in the nut *f*. Other means of anchoring this end of the spring may be employed.

It will be seen from Fig. 1 that the nut is 110

at about its maximum outward position and that the spring lies flat along the inside of the barrel preferably in a groove a' while in Fig. 2 and by the turning of the finger-piece h , the nut has traveled a short distance along the screw e inside the barrel and in so doing has pressed against the end of the spring and bent or bowed the same so as to press down the plate c onto the sac b and compress it. It will be obvious that a few easy rotations of the part h in one direction will compress the sac while reverse rotation will allow it to expand and thus it is a very easy matter to fill the pen.

Fig. 3 shows on enlarged scale how by stamping a lug or clip c' from the plate c and passing the said lug through two holes j' in the spring j , a simple and effective connection between the spring and the plate are obtained without any riveting, soldering or other binding means.

In Fig. 4 which is a cross section about the line 4—4 of Fig. 2, I have shown the nut f of cross bar formation and have illustrated how by fitting the same into the before-mentioned groove a' , and in another short groove a^2 , at the rear end of the barrel, a simple method preventing rotation of the nut in its

backward and forward movements is obtained.

What I claim and desire to secure by Letters Patent is:—

1. In a fountain pen, a hollow barrel, a compressible sac therein, a spring for compressing the sac, a slidable nut engaging one end of said spring, a screw engaging the nut for traversing the same forwardly and also backwardly, and means attached to the screw for moving the latter as desired.

2. In a fountain pen, a hollow barrel, a compressible sac therein, a spring for compressing the sac, a nut slidably and non-rotatably mounted within the barrel and engaging one end of said spring, a screw engaging the nut for traversing the same forwardly and also backwardly, and a rotatable finger piece, outside of the barrel and attached to the screw, for moving the latter as desired.

In witness whereof I have hereunto set my hand in presence of two witnesses.

ARTHUR LICHFIELD SOWERBY.
